UNITED STATES PATENT OFFICE.

FRIEDA RUBEN, OF ST. LOUIS, MISSOURI.

DESIGN FOR A CHAIR OR SIMILAR ARTICLE.

Application filed March 18, 1926. Serial No. 16,914. Term of patent 7 years.

To all whom it may concern:

Be it known that I, FRIEDA RUBEN, a citizen of the United States, residing at the city of St. Louis, in the State of Missouri, have invented a new, original, and ornamental Design for a Chair or Similar Article, of which the following is a specification, reference being had to the accompanying drawing, forming part thereof.

The figure is a front elevation of a chair or similar article, showing my new design. The material used in covering the chair is shown as having a Paisley design, but the drawing is not lined to indicate color.

I claim:

The ornamental design for a chair or similar article, as shown and described.

FRIEDA RUBEN.
